COMBINATION BEVERAGE PREPARING AND DISPENSING MACHINE

Leon Hyzen, Chicago, Ill., assignor to United Coffee Corp., a corporation of Illinois

Application May 9, 1957, Serial No. 46,077

Term of patent 14 years

(Cl. D52—3)

The opposite side of the machine not shown is the same in appearance as the side shown.

The dominant features of my design are shown in solid lines.

I claim:

The ornamental design for a combination beverage preparing and dispensing machine, as shown and described.
